UNITED STATES PATENT OFFICE.

WILLIAM WALKER WILKISON, OF AVALON, MISSOURI.

ANCHOR.

Application filed October 27, 1922. Serial No. 597,285.

To all whom it may concern:

Be it known that I, WILLIAM W. WILKISON, a citizen of the United States, residing at Avalon, in the county of Livingston and 5 State of Missouri, have invented certain new and useful Improvements in Anchors, of which the following is a specification.

My invention relates to anchors which may be used for a variety of purposes and 10 especially for holding the lower ends of guy wires attached at their upper ends to telegraph and other posts, and one object is to provide a substantial device of this character which is simple in construction and operation.

Another object is the provision of means for taking up slack in the guy wires, and means for preventing the anchor itself from working loose after being installed.

20 Other objects will hereinafter appear, and in order that the invention may be fully understood, reference will now be had to the accompanying drawing, in which:

Fig. 1 is a side elevation of the device with 25 the lower portion of a guy wire attached thereto.

Fig. 2 is an enlarged broken vertical section taken on line II—II of Fig. 3.

Fig. 3 is an enlarged cross section on line 30 III—III of Fig. 1.

Fig. 4 is a broken detail side elevation of a spreader and a portion of a rod to which said spreader is fixed.

Fig. 5 is an inverted plan view of a member 35 threaded upon the lower end of the rod and provided with a plurality of flukes.

Fig. 6 is a detail of one of the flukes.

Fig. 7 is a cross section of said fluke.

In carrying out the invention, I employ a 40 rod 2 having threads 4 and 6 at its upper and lower ends, respectively, the threads at one end being right threads and those at the opposite end being left threads for a purpose which will hereinafter appear.

45 8 designates a conical spreader fixed to the rod 2 at a point just above the threads 6. Said conical spreader 8 tapers downwardly and has a plurality of ratchet-like shoulders 10 with abrupt faces 12.

50 14 designates a member which is threaded upon the threaded lower portion of the rod 2. Said member 14 has a plurality of openings 16 extending therethrough and preferably spaced equal distances apart.

55 18 designates a plurality of flukes having reduced lower ends 20 which extend through

the openings 16 and are secured in place by suitable means such as a wire 22. The upper ends 24 of the flukes 18 are curved outwardly and have sharpened edges 25. Each fluke 60 18 has a relatively wide longitudinal edge 26 for engagement with any of the abrupt faces 12 of the shoulders 10 on the spreader 8.

28 designates an element threaded upon 65 the threaded upper end of the rod 2. Said element 28 has a pair of upwardly extending arms 30 terminating in eyes 32, to which the lower portion of a guy wire 34 may be 70 readily connected. The element 28 may be 75 locked at any point of its adjustment by a jamb nut 36 engaging the threads 4.

In practice when the anchor is to be installed in rock or other hard material a hole is drilled to the desired depth and of sufficient diameter to freely admit the spreader 8 and the flukes 18 when the latter are adjusted with the member 14 to the lower position indicated by the dotted lines, Fig. 1. The rod 2, together with the flukes 18 and 80 the spreader 8 are inserted in the hole, the upper end of the rod 2 being allowed to extend out of the hole at approximately the length of the threaded portion 4. After the guy wire 34 has been connected to the telephone or other post to be supported the 85 lower ends of the two strands are attached to the eyes 32 of the arms 30. The rod 2 is then rotated by means of a wrench or other suitable tool in a direction to cause its 90 threaded portion 6 to pass downwardly in the member 14 and the element 28 to pass downwardly upon the threaded portion 4 until the desired tension is obtained upon the guy wire 34. When rotating the rod 2 95 the element 28 is held from rotating so that it will travel downwardly upon said rod 2, as stated. As the rod 2 moves downwardly, the spreader 8 travels therewith and spreads the flukes 18 apart until the upper edges 25 100 become firmly embedded in the walls of the hole, so that the anchor cannot be withdrawn. Owing to the shape of the shoulders 10, the spreader 8 is free to rotate with the rod 2 while the same is being screwed downwardly in the member 14 to tension the guy wire 34, but after the desired tension is had the rod 2 cannot be unscrewed owing to the abrupt faces 12 coming into contact with the corresponding edges 26 of the flukes 18. 110 The element 28 is also prevented from coming loose by means of the jamb nut 36 which

is screwed firmly against the lower end of said element 28, as shown by Fig. 1.

From the foregoing description it is apparent that I have produced an anchor embodying the advantages above pointed out, and while I have shown and described the preferred construction, combination and arrangement of parts, I reserve the right to make such changes as properly fall within 10 the spirit and scope of the appended claims.

Having thus described my invention, what I claim and desire to secure by Letters Patent, is:

1. A device of the character described consisting of a rod, a member threaded upon one end of said rod, flukes loosely connected to said member, and a spreader fixed to the rod to spread the flukes apart when the rod is screwed into the member, said spreader having means which positively engage flukes and prevent the rod unscrewing from the member.

2. A device of the character described consisting of a rod, a conical spreader fixed to said rod and provided with ratchet-like shoulders, a member threaded upon said rod, and flukes carried by said member and adapted to be forced outwardly by the spreader, an edge of each fluke being adapted to engage 20 a shoulder on the spreader and prevent the

rod unscrewing from the threaded member.

3. A device of the character described consisting of a rod, a member threaded upon one end of said rod, flukes loosely connected to said member, a spreader fixed to the 35 rod to spread the flukes apart when the rod is screwed into the member, said spreader having means which positively engage the flukes and prevent the rod unscrewing from the member, and an element threaded upon 40 the other end of the rod and provided with arms, for the purpose described.

4. A device of the character described consisting of a rod, a member threaded upon one end of said rod, flukes loosely connected to said member, a spreader fixed to the rod 45 to spread the flukes apart when the rod is screwed into the member, said spreader having means which positively engage the flukes and prevent the rod unscrewing from the 50 member, an element threaded upon the other end of the rod and provided with arms, and means on the rod for locking said element at any point of its adjustment.

In testimony whereof I affix my signature, 55 in the presence of two witnesses.

WILLIAM WALKER WILKISON.
